Des. 212,848
Patented Dec. 3, 1968

212,848
DENTAL TRAY FOR FULL JAW IMPRESSIONS

Gaylon T. Westlund, 4732 Virginia Ave., Minneapolis,
Minn. 55428, and Nels E. Neslund, 4241 N. Twin Oak
Lane, Robbinsdale, Minn. 55422

Continuation of design applications Ser. No. 6,403,
Mar. 28, 1967, and Ser. No. 9,198, Oct. 30, 1967.
This application Mar. 29, 1968, Ser. No. 11,537

Term of patent 14 years

(Cl. D24—1)

FIG 1

FIG 2

FIG 3

FIG 5

FIG 4

Fig 6

Fig 7

Fig 8

Fig 9

FIG. 1 is a perspective view of a dental tray for full jaw impressions showing our new design;

FIG. 2 is an elevational view of the tray as seen from the right side;

FIG. 3 is a bottom plan view of the tray;

FIG. 4 is an end elevational view of the tray as seen from the open end;

FIG. 5 is an end elevational view of the tray as seen from the closed end;

FIG. 6 is a perspective view of a modified embodiment of the dental tray shown in FIG. 1;

FIG. 7 is an elevation as seen from the right side of FIG. 5, the opposite side is a mirror image of the side shown;

FIG. 8 is a bottom plan view of the tray; and

FIG. 9 is an end elevational view of the tray as seen from the open end.

This is a continuation of design applications Serial No. 9,198 filed October 30, 1967, and Serial No. 6,403 filed March 28, 1967, and now abandoned.

We claim:

The ornamental design for a dental tray for full jaw impressions, as shown and described.
